UNITED STATES PATENT OFFICE.

GEORGE VOELKER, OF ST. PAUL, MINNESOTA.

TYPE-WRITING MACHINE.

1,153,651.

Specification of Letters Patent. Patented Sept. 14, 1915.

Application filed November 23, 1909. Serial No. 529,573.

To all whom it may concern:

Be it known that I, GEORGE VOELKER, a citizen of the United States, residing at St. Paul, in the county of Ramsey and State of Minnesota, have invented certain new and useful Improvements in Type-Writing Machines, of which the following is a specification.

My invention relates to improvements in typewriting machines of the class known as "front strike" or "writing in sight" machines, wherein the type is arranged to strike the platen in front and in a plane vertical or vertically inclined, and wherein the ribbon 10 is supported in a vibratory carrier; and further of the class wherein the carriage is releasable from its escapement or locking devices through the actuation of a finger key at the key board; and still further of the 15 class wherein the type carrying bars are pivotally hung in a vertical, or vertically inclined, plane and arranged concentric to the printing point.

My invention relates more particularly to 20 means for actuating the printing instrumentalities independent of the movement of the carriage.

On machines of the class above referred to, the writing of lines consisting of dots, 25 dashes, or other marks, becomes a tedious and tiresome task, consuming much time and energy, in that it involves a continuous and successive depressing and releasing of a key or key lever by the operator of the machine.

30 This consumption of time and energy, not only works a hardship upon the operator of the typewriting machine but has effectually limited the usefulness of the typewriting machine, itself, in that it has been found 35 profitable and safer to do some classes of work with the pen on lined paper, in order to avoid confusion and sometimes costly errors that arise through the absence of lines to 40 guide the eye of the reader. For example in the billing of goods on writing machines 45 of the class above referred to, where long columns of items and their prices are widely separated by blank spaces, the reader not infrequently resorts to the use of a straight 50 edge or ruler to guide the eye across the sheet. To connect the columns thus separated with lines of dots or dashes on a typewriting machine in the ordinary way would consume too much time. The usefulness of

the present typewriting machine is still further restrained in that classes of work requiring vertical lines (such as the insertion of special columns in billing) must be done by hand.

The object of my invention is particularly 55 to provide improved means for writing lines consisting entirely or in part of periods, dashes or other marks in rapid succession without the usual attendant tedious labor and expenditure of time.

A further object is to provide improved 60 means for underscoring words, or groups of words, rapidly and accurately as by means of overlapping dashes.

A still further object is to provide improved 65 means for writing dotted lines by supplying auxiliary marking mechanism without disturbing the regular printing instrumentalities, without disturbing the usual typebars, but nevertheless striking the same 70 ribbon in the same place that is struck by the aforesaid instrumentalities.

A still further and more specific object is 75 to provide improved means for writing vertical lines of overlapping dashes or lines 80 of dots on the paper carried by the platen.

To the above and other ends, the invention 85 consists in the features of construction, combination and arrangement of parts hereinafter more particularly described and claimed.

My invention is shown as applied to the well known Remington front strike typewriting machine, but it is to be understood 90 that said invention may be embodied in other forms of writing machines, including those of the flat and stationary platen type.

In the accompanying drawings forming 95 part of this specification, Figure 1 is a perspective view of the invention shown in solid lines, and attached to a typewriting machine; Fig. 2 is a perspective view of the air or gas cylinder and its pipe connection with the engine, some of the parts being broken away; Fig. 3 is a vertical section of the 100 lower part of the air or gas cylinder on a line central of the pipe connection; Fig. 4 is a sectional view on line α — α of Fig. 3; Fig. 5 is a plan view of the valve disk; Figs. 6 and 7 are plan views of the liner carrier 105 and portions of the engine, Fig. 7 showing the liner on the printing point; Fig. 8 is an enlarged perspective view of the liner and

liner carrier; Fig. 9 is a side elevation of the liner and a portion of the carrier; Fig. 10 is a perspective view of the carriage speed control showing a portion of the front bar 5 of the carriage and of the main frame; Figs. 11 and 12 are enlarged longitudinal sectional views of the engine showing the piston in its two extreme positions; Fig. 13 is a side elevation of the distributing valve; Fig. 14 is 10 a sectional view on line $y-y$ of Fig. 11; Fig. 15 is a sectional view on line $Z-Z$ of Fig. 11; Fig. 16 is a perspective view of the carriage speed control and the carriage release and ribbon carrier mechanism; Fig. 17 15 is a vertical sectional view of the upper portion of the auxiliary key; Fig. 18 is a perspective view of the engine bracket and the liner carrier support, showing a fragment of the engine; Fig. 19 is a plan view of the 20 engine, screwed in position on the main frame, showing the ribbon carrier and printing point; Fig. 20 is a perspective view of a sheet of paper, showing the various kinds of work executed with the invention; Fig. 25 21 is a diagrammatic view of the usual type bar actuating mechanism.

Referring to Fig. 1 of the drawings A represents in a conventional manner the rectangularly shaped main frame of a 30 Remington front strike typewriting machine, A^3 the top plate thereof, B the platen on the carriage, and C the carriage. D represents the carriage release lever, E the ribbon carrier, F the ribbon, G the spring 35 drum, H the type bars radially hung and concentric to the printing point 47, I the carriage scale, J the column selector keys for operating the tabulator mechanism, K the type bar keys, L the rock shaft, M the 40 universal bar, and N the bar lifting crank arm.

Referring to Fig. 16 of the drawings O represents the ribbon crank arm, P the ribbon lever link, and Q the ribbon lever. S 45 represents the selector rod connected with fulcrumed lever T, said lever carrying at its inner end a pinion U. V represents the escapement shaft carrying at its inner end a pinion W, which meshes with the rack X 50 carried by the carriage, the shaft V carrying at its outer end escapement wheels Y-Y, said wheels being shown locked by the escapement dog Z.

$a^1, a^2, a^3, a^4, a^5, a^6, a^7, a^{10}$, and a^{11} are 55 journal bearings or pivots supported in the main frame A.

A^9 represents a pivotal bearing supported in the side bars of the carriage.

Referring again to Fig. 1 of the drawings, 60 the invention comprises an air compressor 2^a and an air engine 3^a connected by a pipe conductor 4. For the purpose of compressing air and passing it through the conductor into the engine, the compressor 2^a is provided with the comparatively heavy

cylindrical piston 5, said piston fitting snugly and slidably in the vertically arranged cylinder 6, said cylinder having an open top through which the piston may pass and a closed bottom 7. Adjacent to the 70 bottom, and piercing the side walls of the cylinder 6 are openings 8 and 9. The opening 8 is provided with a flap valve comprising a flap 10 screw fastened to the wall of the cylinder at one end and preferably composed of soft rubber or other pliable material and a button 11 attached thereto, the button passing through the wall of the cylinder and fitting loosely in the opening 8. The opening 9 leads into the cylindrical 80 chamber 12, which is surrounded by a shell 13 and formed interiorly in that half of its length farthest from the cylinder, with three longitudinal ribs 14, said ribs forming abutments for the valve disk 15, the 85 interstices between said ribs serving as air passages when the valve abuts against the ends of said ribs as shown in Fig. 3. At its outer end the chamber 12 leads into the pipe conductor 4. The valve 15 is symmetrically 90 notched as at 15^a to form air passages. The piston diameter at its top is reduced to form a central stem 16, which terminates in a forwardly projecting curved hook 17, said hook having on its inner edge, intermediate of its 95 length, a pointer 18. To receive the curved neck at 19 of the hook 17 when the piston is sunken in the cylinder the cylinder has in its upper edge a slot 20. The frame A is provided with a forwardly projecting finger lug A^2 at the top of the post A^1 . The cylinder as shown on the drawings is integral with the corner post A^1 of the frame A. Screw fastened on the front of said post, and extending downwardly and overlapping the upper portion of the cylinder 6, and arranged to be conveniently seen by the operator of the keyboard, is a scale 21, the object of which will be hereinafter more particularly described. Near the top of the cylinder, and preferably integral therewith is a supporting arm 22, said arm projecting in the direction of the carriage travel and parallel thereto. At its outer end said arm 105 slidably supports a finger key 23 the square shank 24 of which fits slidably in the interiorly squared vertical guideway 25, through which the shank passes, the upper portion of said shank being round in cross section and screw threaded to fit a threaded cup nut 26, a spring 27 being interposed between the arm 22 and said nut. The shank 24 has at its top a head 28 against which abuts a spring 29, the opposite end of which 110 engages the slidably mounted collar 30, which surrounds loosely the threadless portion 31 of said shank. The collar 30 is provided with an ear 33 to which is attached one end of a chain 34, the tension rod 35 having 115 connection with the other end thereof, and

120

125

130

passing through an opening 36 in the top of the plate of frame A, the rod 35 terminates in a head 37, said head being slidably and rotatably loosely fitted around the friction rod 38, said friction rod resting on a pair of friction blocks 39 which are preferably integral with the top plate of frame A. The friction rod 38 is provided with a head 40 and a collar 41 at its inner end, the intervening portion of the rod between said head and collar being slidably fitted into the vertical slot 42 of a lug 43, said lug being preferably integral with the front bar 44 of the carriage. The tension rod 35 has, intermediate of its length, turnbuckle connection 35^a to admit of length variation.

The finger key 23 has a downwardly projecting forked extension 45, a fork 46 being adapted to straddle one of the type bar keys, 20 the tines thereof being of sufficient length to maintain engagement with the type bar key during its actuation. The finger key 23 is arranged to engage one of the column selector keys J in its downward movement. 25 The rod 31 with spring 29 and rod 35 may be termed a spring-mounted device.

The conductor pipe 4 extends from the shell 13 in the outer head 13^a of which it has air tight connection, to the left side of 30 the machine, then extending upwardly within the front left hand corner post to the top of the machine, from which latter point it leads radially or diagonally in the direction of the printing point 47, having airtight connection with the air engine 3^a.

The air engine 3^a is so arranged that its longitudinal axis is approximately radial to the printing point, and at a sufficient angle in an approximately horizontal plane to the longitudinal axis B^a of the platen (the drawings showing it at about 45°) to fairly clear the path of the type on the type bar J when it is actuated to swing its type end through an arc to the printing point. The 40 engine is arranged approximately on a level with the longitudinal axis of the platen. The air engine 3^a is provided with a fastening plate 48 which projects at an angle from its side and is preferably integral therewith; 45 and has a pair of slotted holes 49 to receive the screws 50, whereby the engine is rigidly fastened to the frame A. On the engine and projecting rearwardly and toward the printing point 47 and terminating adjacent 50 to the left arm E^a of the ribbon carrier, and in front of the ribbon, is the finger 51, carrying at its outer end the vertical stop pin 52, thus forming a support and guide for the liner carrier. It will be here noted that the 55 ribbon carrier is not central with the printing point, the arm E^a having been arranged farther to the left of said printing point, to accommodate the liner holding mechanism which may be described as follows: The 60 piston rod 53 which is central with the en-

gine bore and alines therewith is formed at its outer end with a plate 54 slidable on finger 51 offset and having an offset slot 55 arranged parallel to said piston rod, said offset being in the direction of the platen B, 70 the slot being adapted to receive snugly the stop pin 52. The plate 54 is comparatively long and narrow, the forward long edge thereof coinciding with the axis of the piston rod. The marking end of said plate, or 75 the narrow edge nearest the platen, is formed parallel to the longitudinal axis of the platen. The plate is well rounded at 54^a to avoid cutting the ribbon during printing operation. Along said narrow edge and on the top of the plate 54, is a clamp lug 56 having a lever lug 57, pierced freely by the screw 58, which latter has screw thread engagement in the plate 54 thus forming a clamp to frictionally engage the bearing 59. 80 The lug 56 is bored to rotatably receive the journal bearing portion 59 of the liner carrier 60. The bearing portion 59 carries at its outer end a liner 61, which may be turned from horizontal to vertical position by turning the bearing 59 in the clamp lug 56 as by 85 means of the carrier 60. It will be noted that the carrier is so bent that its longest portion will be parallel to and just over the piston rod, when the liner 61 is in horizontal 90 position as shown in Fig. 8. The ball 62 serves as a finger hold.

The engine 3^a comprises the pressure case 63, inclosing the distributing valve 64 and striker or piston 65 the latter carrying the 100 piston rod 53. The case 63 is supplied with constant working pressure from the cylinder 6 through the pipe 4.

The distributing valve 64 comprises a cylinder for the head 66 of the striker 65 to 105 operate in, and said valve 64 is reduced in diameter at 67, the latter part performing the valvular function. The valvular extension 68 has an induction port or ports 69 which at the position shown in Fig. 11 admit air from the case 63 to the chamber 70 and an exhaust port or ports 71 which at the 110 position shown in Fig. 12 exhaust air from the chamber 70 to atmosphere through opening 72. The striker or piston 65 is of reduced diameter at 73, said reduced portion being slidably fitted in the fixed sleeve 74, the reduced portion forming a supplemental chamber 75, said chamber being constantly exposed to the working pressure in the case 115 63 through the port 76. The pressure in the chamber 75 serves to return the striker, while the pressure on the shoulder 77 of the valve serves to return the latter, each moving toward the other when pressure is exhausted from the chamber 70 through the port 71, Fig. 12.

The inward stroke of the valve 64 is limited by its abutment against a cushion 79, and the retiring stroke of the striker 65 is 120 125 130

limited by its abutment against the cushion 80 in the valve. The abutment of the striker is thereby elastic, the valve striking the striker with its cushion 80 first. Moreover, 5 the elastic rebound of the valve caused by the retracting abutment of the striker assists the play of the valve by starting it on its outward movement while air is entering ports 69 to the same purpose.

10 In operation the reciprocations of the striker or piston, and the annular valve 64 in opposite directions occur as follows. Air admitted through the pipe conductor 4 under constant pressure, enters through the 15 port 69 and acting on the enlarged surface area of the striker drives the same with force against the platen through the medium of the piston rod 53 as shown in Fig. 12. The pressure then acting on the valve 20 64 reciprocates it until the exhaust port 71 extends beyond the end of the bushing or valve seat 82 where the prevailing body of air is exhausted. The pressure in the chamber 75 acting on the shoulder 83 of the 25 striker returns the same to its inner position as shown in Fig. 11. The air pressure then acting on the shoulder 77 of the valve moves the valve until the port 69 is again open for the induction of pressure and the same 30 movements are repeated. A spring 84 is interposed between the head 63^a and the striker 65. As shown in the drawings the air chamber 85 of the cylinder is sufficiently large, as compared with the air chambers 70 35 and 75 of the engine, to supply through the pipe conductor 4, and through the medium of the descending plunger or piston 5 a sufficient quantity of compressed air to cause the striker 66, and therefore the piston rod 40 and the liner or marker carrier, to make a plurality of successive forward and backward strokes, the marking end of the carrier striking the ribbon and the paper covered platen with every forward stroke and printing an impression of the liner on said paper. It is intended that the cylinder chamber 85 45 be of sufficiently ample proportions to furnish enough air for the writing of a full line of marks across a sheet of paper.

50 It will be evident that the weighted piston 5 insures a uniform pressure in the chamber 85 during its entire downward stroke, in that the weight is constant, thus imparting to the piston or striker, and therefore to the liner 61 uniform consecutive vibrations, which in turn insures equidistant and regular impressions of the liner on the paper carried by the platen.

The operation of the invention is as follows: In normal position the piston 5 is sunken in the cylinder 6, the neck 19 of the hook 17 resting on the bottom of the slot 20 in the cylinder wall. The liner 61 is normally (when the invention is out of use) 55 in a receded, or partially receded, position

(Fig. 6 showing the liner fully receded from the platen) its position depending upon the position of the piston 65, which is free to stop at any point between the spring 84 and the cushion 80, as shown in Fig. 11, the spring 84 performing the combined functions of a cushion and a means for preventing the liner 61 to stop at the printing point (Fig. 7) and thus block the path of usual typebars of the machine. 70 When the piston under pressure in its forward stroke carries the liner against the platen the impact compresses the spring 84, which, in turn, causes the piston to rebound, carrying the liner with it, thus making interference with the type bars impossible, as shown in Fig. 6 in which a type bar J is 80 shown in dotted lines.

In order to avoid the paths of the type on the type bars H, I arrange the engine 3^a at 85 an angle with the longitudinal axis of the platen, as has been previously explained. With this arrangement of the engine 3^a the piston and therefore the liner strike the platen at an angle, with a general tendency 90 to glance off in a resultant direction after contact with the platen. In order to counteract the referred to tendency of the glancing off of the liner, I have located the engine to the left of the printing point, so 95 that the direction of the piston rod 53 in its forward printing stroke will be opposed to the direction in which the carriage is traveling during printing operation. Thus the platen on the moving carriage in opposing 100 the direction of the striking piston tends to 105 repel the liner during the moment of impact and thus prevents slipping and dragging, which would result in blurred impressions on the paper.

To further control the liner during contact with the platen, the finger 51 and its pin 52 are provided; the pin fitting snugly into the slot 55 of the plate 54, said plate, working back and forth during printing operation. The pin 52 is so arranged on the finger 51 that the arrival of the pin at the end of the slot 55, and the arrival of the liner 61 at the printing point 47, occurs simultaneously (Fig. 7). Thus the direction of the 115 force in the piston rod 53, through the medium of the pin 52, is diverted into a resultant direction nearer to right angles with the longitudinal axis of the platen. The engine bracket 48 is provided with slotted 120 holes 49, by means of which the liner 61 may be adjusted to be brought nearer to, or farther from, the printing point. It will be evident that the rate of speed at which the carriage travels past the rapidly vibrating liner will determine the space which separates the written dots or dashes on the paper. To use only the column selector keys for releasing the carriage without providing a 125 brake retarding means for checking its speed 130

would be impracticable, because the carriage would travel too fast. To control the speed of the carriage I provide the friction rod or wire 38 which is attached to the carriage as by means of lug 43. When the key 23 is depressed the chain 34 will be drawn taut, pulling the rod 35 downwardly and the rod 38 against the friction blocks 39, thus causing said rod 39 to resist longitudinal movement. The resistance against movement in the rod 39, may be varied by varying the amount of pull in the rod 35, which is accomplished by shortening or lengthening the same as by means of the turnbuckle 35^a. The spring 29 affords a cushion as well as permitting the key 23 to be still further depressed for the purpose of actuating the keys K and J. The rod 35 should be so adjusted by the use of the turnbuckle 35^a, that pressure will be brought to bear on the rod 38 just after the carriage has been released by the depression of the key J. There is in all tabulator keys a slight surplus of downward travel after its function of releasing the carriage has been performed. Thus the spring 29 may be stiff enough to exert sufficient pressure in a depression of but one-sixteenth of an inch. It is intended to have the head 37 still hanging loosely until just after the carriage is released. (See Fig. 1). It will be noted that the cup nut 26 also permits of adjustment to vary the amount of depression of the key J. The head 37 and the blocks 39 may be termed retarding devices. The spring 29 and the chain 34 render the connections between the carriage and the tabulator mechanism both elastic and flexible.

The depression of key K will depress the universal bar M at M² and thus actuate the ribbon carrier E through the medium of the lever Q, rod P, crank arm O; rock shaft L, and crank arms and links N. The fork 46, however, is designed to depress the key lever K sufficient only to swing in an arc the type 45 of its corresponding type bar H, said bar turning on its pivot a¹⁰ through the lever pivot a¹¹ in the frame A (Fig. 21) through but a fraction of its stroke, thus preventing interference at the printing point with the liner 61, during printing operation but nevertheless raising the ribbon carrier from the dotted line e to the dotted line i, as shown in Fig. 16, thus bringing the ribbon into the path of the liner 61 and over the printing 50 point 47. The key J is the usual column selector key of the Remington machine, whereby the carriage is released and caused to travel to left through the medium of the spring drum G. Fig. 16 shows the general principle employed. the depression of the key J actuates the fulcrumed lever T as by means of rod S thus raising the rack X about its pivots a⁹ and disengaging the pinion W, which latter is normally held locked as by means of wheels Y—Y, and dog Z,

said wheels and pinion being rigidly mounted on the shaft V. Thus it will be evident that the depression of key 23 results in the release of the carriage from its locking devices, causing it to travel to the left through the medium of the spring drum G, the controlling of the speed of the carriage and the raising of the ribbon into the type path. If, now, the operator places the thumb of the right hand on the finger lug A² and with the forefinger catches the hook 17 from below, pulling it with the piston 5 upward, the flap valve 10 will move inwardly through the medium of the atmospheric pressure outside the cylinder and the vacuum created in the chamber 85 by the rising piston. Air will rush into the cylinder through the opening 8, until the piston has reached its extreme height (Fig. 1). During the piston's upward travel, the valve 15 will close the opening 9, due also to atmospheric pressure without and the vacuum within the chamber 85, thus preventing the actuation of the engine by the rushing in of air through the port 72, which would occur during the rise of the piston 5 if the opening 9 were left open. If, now, the operator removes his hand and allows the piston to descend into the cylinder 6 by its own weight, the valve 15 will be forced against the ribs 14 in the chamber 12 and the air will pass through the notches 15^a in the valve 15 into the pipe 4 and into the engine 3^a, causing the piston 65 to reciprocate or vibrate rapidly and therefore also the liner, said liner striking the ribbon and paper covered platen with every forward stroke. When the liner at the end of the piston rod 53 in its rapid movement forward collides with the moving platen, the two are instantly separated by the spring 84, the impact of the blow being sufficient to make imprints through several carbon sheets. If the impact is found too great and the platen becomes pitted, the engine may be adjusted by means of slotted holes 49.

The reciprocating piston 65 of the engine may be stopped instantly by depressing the button 11 on the flap valve 10 which effects the rushing out of the air in the chamber 85 and the rapid descent of the compressor piston 5. It will be evident, then, that in order to write full lines of dots, dashes, or other marks, across a sheet from left to right, it is simply necessary to lift the compressor piston 5 to its upward limit, with the right hand, and with the left hand depress the key 23 to its downward limit. If, however, only short portions of dotted lines are required the piston 5 may be raised to any desired mark on the scale 21, the pointer 18 on the hook 17 indicating the level of said piston. Thus the piston 5 may be raised to write any desired length of line on the paper, thus obviating the necessity of using the button 11 except on special occasions or in emergency,

and of raising the piston to its full height except when necessary. The scale 21 is marked to correspond with the scale 1. If, for example, it is desired to write dotted lines from the point 50 on the carriage scale, it is only necessary to raise the piston 5 to the 50 mark on the scale 21, and allow the piston to descend.

It will be evident from the foregoing that 10 the liner 61 may be reciprocated without using the key 23 at all, or, in other words, the carriage may remain unmoved during the actuation of the engine 3a.

Referring to Fig. 8 it will be noted that 15 the liner 61 is not mounted central on the portion 59 of the carrier, but that the end 61a to the left of the portion 59 is considerably longer than the portion to the right of the portion 59. Referring to Fig. 9 the carrier 60 is shown in upturned position, the liner 61 standing vertical, the carrier 60 having been turned in the journal box 56 until the liner 61 abuts against the stop pin 56 (Fig. 8) which limits its movement. The 20 long end 61a of the liner 61 is now turned downwardly and projects beyond the upper edge of the ribbon F when said ribbon is in its normal position as shown in Fig. 9. If, now, the liner 61 is reciprocated it will print 25 an impression on the paper of that portion of itself which extends below the upper edge of the ribbon F, thus obviating the necessity of raising the ribbon carrier. It will be evident that if the operator turns the thumb 30 wheel B² with his left hand, at the same time holding the platen carriage stationary, and raises the piston 5 with his right and then allows it to descend and then turns the handle D² with his right which moves the ribbon 35 from one spool to the other, the liner 61 will write vertical lines of dashes or solid lines, according to the speed at which the thumb wheel B² is turned.

The ribbon mechanism actuated by the 40 handle D² is not shown, but it is to be understood that the invention is shown as applied to a Remington front strike machine, which has a handle D² on either side of the machine for transferring the ribbon from one 45 spool to the other.

It is obvious that the details of the device 50 may be variously modified without departing from the principles of the invention, the scope of which is defined in the claims.

55 I claim as my invention:

1. In a typewriting machine, the combination with a platen and the main typewriting instrumentalities, of a vibratory liner or marker co-operating therewith and 60 a weight controlled actuating device for intermittently vibrating said liner or marker, said device being independent of said main typewriting instrumentalities.

65 2. In a typewriting machine, the combination with a platen, carriage, keys and key

levers, of a liner or marker adapted to vibrate against said platen concurrently with the movement of said carriage and actuating means independent of the carriage and said keys and key levers.

3. In a typewriting machine, the combination of a rotary platen, a vibratory liner or marker, a depressed key and automatic air actuated actuating means for imparting, by a single depression of said key, a succession of printing strokes to said liner or marker concurrently with the rotation of said platen.

4. In a typewriting machine, the combination of a paper carrying platen and air 80 actuated marking or lining instrumentalities controlled by a slidable weight adapted to effect a plurality of imprints on the paper when said weight is slid in one direction.

5. In a typewriting machine, the combination with a platen and the main typewriting mechanism, of a marker or liner, and weight controlled means independent of said main writing mechanism for successively 90 moving said type back and forth.

6. In a typewriting machine the combination with a platen, of a vibratory marker or liner carrier, and power driving means for automatically moving a plurality of 95 times said vibratory marker or liner carrier, through its full stroke, uninterruptedly to said platen and then away from said platen.

7. In a typewriting machine, the combination with the frame, platen and pivoted 100 type bars, of an auxiliary liner or marker carrier arranged to reciprocate in said frame, on a level approximately in line with the longitudinal axis of said platen and adapted to clear said type bars when they 105 are caused to move about their pivots.

8. In a typewriting machine, in combination with main type bars and a movable platen, of a marking or lining device arranged to reciprocate in a flat plane parallel 110 to the longitudinal axis of said platen, so that, when said platen and said marking or lining device are moved they will approach each other at an angle of about 135 degrees.

9. In a typewriting machine the combination with a platen, a frame, type, and type bars pivotally mounted on said frame, of a liner or marker carrier arranged to vibrate above said type and type bars and inclined 115 from the perpendicular with respect to the axis of said platen, and automatic actuating means to vibrate said liner or marker carrier.

10. In a typewriting machine the combination with a frame, type bars pivotally 125 hung therein and adapted to swing their type ends through an arc or path to the printing point, of an auxiliary vibratory liner or marker arranged above said type bars and adjacent to said arc or path, and 130

power driven actuating means to effect the movement of said vibratory liner or marker into said arc or path to the printing point.

11. In a typewriting machine the combination with a typewriter frame and main type bars in said frame adapted to swing their ends to the printing point, of a vibratory lining or marking device including a marker or liner arranged above said main typebars, and adjacent to the range of action of the ends thereof, and independent power actuated mechanism for said vibratory lining or marking device to project said marker or liner into and out of said range of action.

12. In a front strike typewriting machine the combination with a typewriter frame, main key actuated typewriting instrumentalities and a carriage, of an auxiliary vibratory marking or lining mechanism between said carriage and said frame and independent air driven actuating mechanism for said auxiliary marking or lining mechanism.

13. In a typewriting machine the combination with a carriage, main type bars, and a platen, of a slidable auxiliary liner or marker carrier, actuating means therefor, said parts being so constructed and arranged that the printing point on the platen and the liner or marker carrier approach each other when actuated at an angle of about 135 degrees.

14. In a typewriting machine, the combination with a frame, a platen carriage and key actuated type bars, of independent marking or lining instrumentalities on said frame arranged opposite and in front of said platen between the carriage and said frame and a power conductor connecting said instrumentalities with a source of power.

15. In a typewriting machine the combination with a platen and a ribbon carrier, said carrier including a pair of arms, of a vibratory liner or marker arranged to strike the printing point on said platen at an obtuse angle and between the arms of said ribbon carrier, and a support for said vibratory liner or marker adjacent to said ribbon carrier.

16. In a typewriting machine, the combination with main typebars, a platen and a ribbon carrier, of an auxiliary liner or marker carrier adapted to slide to the printing point and a support therefor adjacent to said ribbon carrier, said support including a means for diverting the direction of travel of said liner or marker carrier so that its marking end will strike the platen in a direction at right angles to its surface.

17. In a typewriting machine in combination with main type bars and a revolute platen, an auxiliary liner or marker carrier slidably supported adjacent to the printing point and having its longitudinal axis arranged at an acute angle with the

longitudinal axis of said platen and a power conductor operatively connected with said liner or marker carrier at one end and with a source of power at its other end.

18. In a typewriting machine the combination with a horizontal platen and a ribbon carrier, a reciprocating liner or marker carrier arranged radial to the printing point and including guiding means at its outer end, and a support therefor adjacent to the ribbon carrier, said support cooperating with said guiding means.

19. In a typewriting machine, in combination with a rectangularly shaped typewriter frame, its main type bars, and a ribbon carrier, an auxiliary vibratory liner or marker carrier slidably supported at the top of said frame and adjacent to said ribbon carrier and arranged to vibrate in a diagonal direction with respect to said frame toward the said ribbon carrier and a conductor connecting said auxiliary type with a source of power.

20. In a typewriting machine the combination with the rectangular top of a typewriter frame and the regular typewriting instrumentalities, of an auxiliary marking or lining mechanism arranged diagonally on said top of said frame and above and out of the way of said regular typewriting instrumentalities and directed toward the printing point, and a power feeding tube connected with that end of said auxiliary marking or lining mechanism which is farthest from the printing point.

21. In a typewriting machine, in combination with main type writing instrumentalities, auxiliary marking or lining mechanism, power supplying mechanism therefor and indicating means for apportioning the supply of power.

22. In a typewriting machine, in combination with main type writing instrumentalities, auxiliary marking or lining mechanism, power supplying means for said mechanism and indicating means for preliminarily determining the amount of power to be supplied to execute a predetermined amount of writing.

23. In a typewriting machine the combination with tabulator mechanism, main printing instrumentalities and a carriage, of auxiliary, air-actuated marking or lining mechanism, a power supplying tube connected therewith and a key at the key board to cooperate with said tabulator mechanism for the purpose of releasing the carriage.

24. In a typewriting machine, the combination of a vibratory mechanism, actuating mechanism therefor and a visible scale whereby said actuating mechanism may be preliminarily set to actuate said vibratory mechanism for a predetermined length of time.

25. In a typewriting machine the combi-

nation with the main printing instrumentalities and the main frame, of auxiliary air-driven marking or lining mechanism and a power supplying device for said auxiliary mechanism adjacent to the keyboard and attached to said frame.

26. In a typewriting machine the combination with a carriage its escapement devices, and the main typewriting instrumentalities, of automatic, air-actuated marking or lining devices, independent actuating means therefor and a key for releasing the carriage from its escapement devices.

27. In a typewriting machine the combination with a platen carriage and its escapement devices, of a key, a vibratory marker or liner, and a weight controlled means for successively vibrating said marker or liner during the travel of said carriage in the directions of its feed by a single depression of said key.

28. In a typewriting machine the combination of marking or lining mechanism, a power supplying apparatus therefor, including an air chamber, and a hand-operable valve for exhausting the air from said chamber at the will of the operator.

29. In a typewriting machine the combination of mechanically vibrated marking or lining devices, and a power supplying apparatus therefor, said apparatus including a weight and a finger hook on said weight for raising the same.

30. In a typewriting machine the combination with the main typewriting instrumentalities, of auxiliary, automatically-operated marking or lining means and a power supplying apparatus for said means, said apparatus including a piston and cylinder.

31. In a typewriting machine the combination of lining or marking instrumentalities operatively connected with an air receptacle, means for compressing the air in said receptacle and a hand operable outlet valve for the purpose of reducing the pressure in said receptacle at the will of the operator.

32. In a typewriting machine the combination with the main printing instrumentalities, said instrumentalities including a vibratory ribbon carrier, of auxiliary marking or lining means, actuating means for said printing means, and auxiliary, key-actuated means for moving and holding the ribbon carrier in coöperative relation with said printing means.

33. In a typewriting machine, in combination with key-actuated main typebars and main ribbon vibrating mechanism coöperatively connected with said main typebars, of auxiliary marking or lining and ribbon vibrating means, and a key 23 for the purpose of moving the main type bars and main ribbon vibrating mechanism a predetermined amount so that the main typebars will not

interfere with said auxiliary marking or lining means during operation.

34. In a typewriting machine the combination with printing keys, a carriage and key-actuated printing instrumentalities, of a vibratory marker or liner and actuating means independent of said carriage and said key actuated printing instrumentalities to cause said vibratory marker or liner to print a number of times in succession in a line from left to right.

35. In a typewriting machine the combination with a carriage and the main typewriting instrumentalities, of auxiliary marking or lining means, actuating devices connected therewith, and adjustable means for controlling the speed of the carriage.

36. In a typewriting machine the combination of a reciprocatory marker or liner, and actuating means for said marker or liner, said means including an indicator whereby the length of the period of actuation may be measured.

37. In a typewriting machine the combination with a platen, a carriage, and escapement devices therefor, of a vibratory liner or marker, actuating means to vibrate said liner or marker against the platen and speed controlling means for said carriage.

38. In a typewriting machine the combination with a platen and a carriage, of a reciprocatory liner or marker, independent actuating means therefor and speed controlling means for said carriage.

39. In a typewriting machine the combination with a platen and a carriage, of automatic lining or marking instrumentalities and means for controlling the speed of the carriage to effect variable spacing between the imprints on the paper.

40. In a typewriting machine the combination with a carriage, escapement devices and releasing means for the carriage, of a vibratory marker or liner, actuating means therefor, and means for releasing the carriage and for controlling the speed thereof.

41. In a typewriting machine the combination with a carriage and releasing means for said carriage, of lining or marking instrumentalities, automatic actuating means therefor, and means for simultaneously releasing the carriage and controlling the speed thereof.

42. In a typewriting machine the combination with a carriage, escapement devices and releasing means for said carriage, of automatic marking or lining mechanism, actuating means therefor, and a key to control the speed of the carriage when said carriage is released from its escapement devices.

43. In a typewriting machine, the combination with a platen, a carriage, driving means for said carriage, a vibratory marker or liner and power driven actuating means

therefor, said actuating means being mounted and inclined with respect to the axis of the platen so that said marker or liner strikes the platen to make an imprint on the paper in a direction inclined to the right when the carriage is traveling to the left.

44. In a typewriting machine, the combination with a group of main type bars and a platen, of a vibratory liner carrier mounted above and independently of said group of type bars, and in a manner with respect to the axis of said platen, so that said type carrier will travel to the platen to effect an imprint on the paper, from a point to the left of a median fore and aft line of the machine.

45. In a typewriting machine the combination with a rotary platen, a marker or liner device, a depressed key, actuating means to effect a succession of printing strokes to said marking or lining device by a single depression of said key, and means for positioning said marking or lining device to effect the marking or lining of vertical lines on the paper when the platen is rotated.

46. In a typewriting machine the combination with a ribbon and its actuating means of automatically operated marking or lining means and independent ribbon raising means to bring the ribbon into printing relation with said marking or lining means.

47. In a typewriting machine, in combination with a platen, of a liner or marker carrier adapted to travel to the printing point, said carrier having a slot parallel

with but offset from its line of travel, and a stop pin supported in the frame of the machine and adapted to work in said slot for the purpose of guiding said carrier and also limit its travel, and by virtue of said offset of said slot, cause said liner or marker to rotate about said pin and thereby effect a perpendicular pressure of the type against the platen.

48. In a typewriting machine, in combination with a platen, of a pin mounted on the frame of the machine, a vibratory marker or liner carrier controlled in its travel to the platen by said pin, adjusting means for changing the position of said pin and said marker or liner carrier relative to the platen, and means for vibrating the marker or liner carrier.

49. In a typewriting machine, in combination with the frame and main type bars adapted to swing their type-ends through an arc or path to the printing point, of auxiliary marking or lining mechanism including a marker or liner and mounted adjacent to said arc or path, power driven actuating means for projecting said marker or liner into said arc or path and automatic means for withdrawing said marker or liner from said arc or path.

In testimony whereof I affix my signature in presence of two witnesses.

GEORGE VOELKER.
